UNITED STATES PATENT OFFICE.

DAVID L. ROSENBERG, OF DORCHESTER, MASSACHUSETTS.

BLOOMERS.

Application filed July 24, 1920. Serial No. 398,620.

To all whom it may concern:

Be it known that I, DAVID L. ROSENBERG, a citizen of the United States of America, and a resident of Dorchester, in the county 5 of Suffolk and State of Massachusetts, have invented a new and useful Improvement in Bloomers, of which the following is a specification, reference being had to the accompanying drawing, forming part thereof.

10 My invention relates to bifurcated ladies' garments, as bloomers, knickerbockers and the like, and has for its object to provide a reinforcement for the garment at the inner and rubbing sides of the legs thereof, which 15 reinforcement is in the nature of an extended gusset reaching all the way down said legs from the crotch of the garment substantially to the leg openings thereof; said gusset being so designed as to provide 20 a substantial width at the crotch and for an appreciable length below same wherefrom the gusset gradually diminishes in width towards the leg opening where the gusset is terminated.

25 Another object of the invention is to provide a bifurcated garment with a reinforcing layer between the legs thereof, reaching all the way down the legs of the garment, for effecting a reinforcing feature to the 30 garment at the wearing section thereof, where the legs of the garment are subjected to rubbing contact and stretch, and where, especially in the case of garments made of silk or silk jersey, the wear is incompatible 35 with and most damaging to the delicate material used in the garment.

To these as well as other ends my invention consists of the novel features of construction, combination, and arrangement of 40 parts set forth in the following specification, and particularly pointed out in the subjoined claim.

The terms employed herein are used in the generic and descriptive sense to designate 45 the elements illustrated, and are therefore not primarily intended as terms of limitation.

In order to illustrate my invention I have shown in the accompanying sheet of drawing 50 an embodiment thereof wherein:

Fig. 1 represents a fragmentary view showing a pair of ladies' bloomers supplied with my invention.

Fig. 2 represents a fragmentary sectional view taken on line 2-2 on Fig. 1; 55

Fig. 3 represents a sectional view taken on line 3-3 on Fig. 1;

Fig. 4 represents a sectional view taken on line 4-4 on Fig. 1;

Fig. 5 represents a sectional view taken 60 on line 5-5 on Fig. 1, showing diagrammatically the setting of the gusset with the garment before joining and seaming the leg of the same;

Fig. 6 represents an enlarged sectional 65 view taken across the seam of the leg of the garment for showing the manner of joining the parts together in said seam.

Fig. 7 represents the correlated gusset pieces before being incorporated into the 70 garment.

Fig. 8 represents a portion of the leg development showing the correlated gusset pieces secured thereto before seaming the leg together; and 75

Fig. 9 represents the garment leg shown in Fig. 8 seamed, wherein the outer edges of the gusset pieces are secured and anchored in the leg seam by the so-called overlock stitch. 80

Like numerals refer to like parts throughout the several views of the drawing.

The numeral 10 represents a bifurcated ladies' garment, as a bloomer, knickerbocker, or the like, which is made up of any 85 suitable material, as silk, silk jersey, or the like, and has the self-closing, gathered top 11 which is drawn on an elastic, tape or band in the usual manner for snugly fitting the waist of the wearer. 12 and 13 are the 90 left and right legs of the garment, respectively, which are shown provided with the ruffles 14 at the extremities thereof, said ruffles being each preferably gathered on elastic bands to yield a snug fit at that point 95 and to permit of stretch when required.

15 and 16 and 17 and 18 represent the gusset pieces which are provided for the legs 12 and 13, respectively, and which are shaped substantially as shown in Fig. 7 and are designed preferably to reach from the crotch 19 to, or near to, the leg extremity 20, as shown in Figs. 1 and 2. Said gusset pieces are preferably made parted, as shown in Fig. 7 and are cut in substantially the shape 105 there shown for affording a substantial

width across the leg for an appreciable length down from the crotch of the garment, as shown in Fig. 2, the idea being to maintain sufficient width to the gusset between 5 the crotch and a point below the knee to assure the necessary width to the gusset to cope with the rubbing conditions there existing due to walking or body actions.

The garment is preferably made up of 10 two main parts forming the legs thereof, as will be understood from Figs. 1, 3, 8 and 9. Fig. 8 represents schematically a development or pattern of one of said legs, and shows the correlated gusset pieces as G_1 and G_2 secured on their outer and opposite edges E to said leg pattern L by the stitching S which reaches from the crotch edge C to the leg opening or outlet end O . The remaining edges of the gussets G_1 and G_2 15 border on the leg pattern L and are stitched in together with the leg seam 21 (as shown in Figs. 1, 2, 5, 6 and 9), and with the joining seam 22 which unite the legs 12 and 13, as shown in Fig. 1. In this manner the gusset 20 pieces are incorporated into the garment, preferably on the inside thereof, as indicated in Figs. 1 and 2, and serve to reinforce the area of the garment subjected to the usual attending wearing strains directed 25 30 35 against. The gusset is designed to amply cover the portion of the garment mostly affected by the rubbing action to which the same is subjected while being worn, and not only does it reinforce and protect the crotch section of the garment but it reinforces and

protects the entire length of leg to a point below the knee joint, and thus greatly adds to the life of the garment.

The gusset may be made up of the same material as the garment, or otherwise, according as may be desired; and in any event the association of said gusset with the garment, as herein disclosed, leaves very little evidence on the outer part of the garment to indicate its presence in the garment. The application of a gusset, as herein disclosed, adds very little to the cost of manufacture of the garment, the work of embodying the same in the garment is simple, and the advantages attained thereby, so far as benefiting the garment is concerned, are obvious and warrant its adoption.

Having thus described my invention in detail, what I claim as new is:

The method of making a bifurcated garment with a reinforcing gusset, comprising securing separate gusset pieces to the sides of the legs while in open form and then joining the sides of the leg and the edges of said gusset pieces by an overlocking stitch, thereby anchoring the central portions of said gusset in said leg seam and finally seaming two gusseted legs together and anchoring the top of the gusset in said leg joining seam.

In witness whereof, I hereunto affix my signature this twenty-third day of July, 1920.

DAVID L. ROSENBERG.
